CAMERA FRONT HOUSING

Norman Ralph Kubnick, Wheeling, Ill., assignor to Bell & Howell Company, Chicago, Ill., a corporation of Illinois

Filed Jan. 28, 1963, Ser. No. 73,334

Term of patent 14 years

(Cl. D61—1)

Fig. 1.

Fig. 2.

FIGURE 1 is a top front perspective view of a camera front housing showing my new design; and

FIGURE 2 is a top rear perspective view thereof.

The bottom of the camera front housing is substantially plain and unornamented.

The broken-line showing of a camera body and lens housing is for illustrative purposes only.

This application is a continuation-in-part of my earlier filed application No. D. 69,710, filed April 9, 1962, now abandoned.

I claim:

The ornamental design for a camera front housing, as shown and described.
